TIE CLAMP

John Yartz, Wilkes-Barre, Pa.

Application October 19, 1937, Serial No. 169,859

2 Claims. (Cl. 173—313)

My invention relates to improvements in electric insulators and more particularly to tie clamps used in connection therewith.

One of the principal objects of my invention is to provide a tie clamp adapted for connection to an insulator whereby electric cables may be quickly and effectively clamped thereto.

Another object of my invention is to provide a clamp of the above described character equipped with means whereby the clamping means is maintained in a locked position.

A further object of my invention is to provide a clamp of the above described character capable of accommodating electric cables of various sizes whereby the same are effectively clamped thereto.

Other objects and advantages will be apparent from the following description, appended claims and annexed drawing.

Referring to the drawing wherein like reference characters designate like parts throughout the several views:

Fig. 1 is a top plan view of my invention illustrating the same as being secured to an electric insulator.

Fig. 2 is a longitudinal section taken on the line 2—2 of Figure 1.

Fig. 3 is a detail transverse sectional view of the cap illustrating the stationary clamping element.

Fig. 4 is a top plan view of a pair of shims employed in connection with the clamping device.

Fig. 5 is a side elevation of the latch member.

In practicing my invention I provide a cap member 5, preferably constructed of relatively stiff sheet metal, formed on the lower circumferentially extending face with a plurality of upwardly extending slots 6 providing a compressible section 7. The top 8 of said cap is of a substantially bulbous configuration and is segmented

40 throughout the length thereof to form a cable receiving passageway 9 through said cap. Interiorly of said cap and adjacent the compressible section there is secured a horizontally extending deck 10, the lower face of which abuts the

45 head 11 of an insulator 12 of typical construction.

One side of the passageway 9 is formed with a wall 13 of substantially semi-circular configuration integral with the top 8 at the upper end and terminating at the lower end in apertured

50 segmented hinge sections 14 as clearly illustrated in Figure 3 of the drawing, said wall constituting a clamping element forming a part of a clamping device. Oppositely disposed from the wall

55 13 is a similar shaped wall 15 or clamping element forming another part of the clamping de-

vice and said wall is fashioned at the lower end with hinge sections fitting the segmented portions of the hinge section formed on the wall 13 and is pivotally connected thereto by a pintle 16.

Pivotally mounted on the deck 10 is a toggle 5 mechanism comprising toggle arms 17, 18 and 19, the lower end of the arm 17 being pivotally connected to the deck and the upper end pivotally connected to ends of the arms 18 and 19. The opposite end of the arm 18 is pivotally connected to the wall 15 and the opposite end of the arm 19 is pivotally connected to an inner end of an actuating lever 20, said lever being pivotally secured to the cap 5 as at 21. Actuation of the lever 20 downwardly towards the insulator, will 10 through the medium of the toggle mechanism, position the clamping element 15 in clamping position relative to the clamping element 13 as illustrated in full lines in Figure 2. Actuation of the lever 20 in an upward direction away from the 15 insulator will, through the medium of the toggle mechanism, position the clamping element 15 in opened or unclamped position relative to the clamping element 13 as clearly illustrated in dotted lines in said figure.

The cap 5 is secured about the head 11 of the insulator by means of a clamping band 22 having pivoted sections 23 embracing and compressing the section 7 about the head and said sections 23 are secured together in clamped condition by 30 means of a suitable nut and bolt 24 as illustrated in Figure 1.

The lever 20 is maintained in clamped position by means of a latch member 25 pivoted to the cap 5, thereby preventing accidental dislodgment 35 of the lever when the same is in clamped condition to maintain an electric cable between the clamping elements.

From the foregoing it will be apparent that a length of electric cable positioned between the 40 clamping elements 13 and 15—when the parts are in opened position—may be effectively clamped therebetween by the actuation of the lever 20 to the locked or clamped position illustrated in full lines in Figure 2 and that a reverse 45 movement of said lever will serve to release the clamping action of the clamping device and permit removal of the cable.

In instances where it is desired to secure cables of a smaller diameter in the clamping device, I 50 provide the walls 13 and 15 with bayonet slots 26 for receiving headed pins secured to shims 27 therethrough and which maintain said shims to said walls. Each of the shims are of a sufficient thickness so that the cable may be effectively 55

clamped therebetween and are provided with cable receiving grooves 28 for embracing the cable.

It will be apparent that cables of various sizes 5 may be effectively clamped between the clamping elements 13 and 15 and securely connected to the insulator.

The outer ends of the lever 20 and latch member 25 are adapted to receive the hook-end of a 10 stick, commonly known as a "hot-stick", for operating the same thereby eliminating the danger to linemen in connecting and disconnecting the cable to the tie clamp.

What I claim is:

15 1. A tie clamp for insulators, comprising, a cap member having a compressible section adapted to fit over the head of an insulator, a clamping band secured about said section, a deck mounted within said cap for abutting engagement with the 20 head of the insulator, a clamping element connected to the top of said cap, a like clamping element pivoted to the first mentioned element and adapted to coact with the latter to clamp an electric cable therebetween, toggle mechanism mount-

ed on said deck and connected to said second mentioned clamping element, and an operating lever pivotally connected to said cap and to said toggle mechanism and operable for moving said second mentioned clamping element into and out of clamping position. 5

2. A tie clamp for insulators, comprising, a cap member having a compressible section adapted to fit over the head of an insulator, a clamping band secured about said section, a deck mounted within 10 said cap for abutting engagement with the head of the insulator, a clamping element connected to the top of said cap, a like clamping element pivoted to the first mentioned element and adapted to coact with the latter to clamp an electric cable 15 therebetween, toggle mechanism mounted on said deck and connected to said second mentioned clamping element, an operating lever pivotally connected to said cap and to said toggle mechanism and operable for moving said second mentioned clamping element into and out of clamping position, and a latch carried by said cap for locking 20 said lever in clamping position.

JOHN YARTZ.
